Patented May 13, 1969

214,141

COIN-OPERATED LOCKER

Ichiro Horikoshi, 1-16, Takasago 8-chome, Katsushika-ku,
Tokyo, Japan

Filed Apr. 24, 1968, Ser. No. 11,609

Term of patent 14 years

Int. Cl. D29—99; D31

U.S. Cl. D69—1

FIG. 1

FIG. 2

FIG. 3

FIG. 4

FIG. 5

FIG. 1 is a view in perspective of the front, top and one end of a coin-operated locker according to the present invention;

FIG. 2 is a front view in elevation of the coin-operated locker shown in FIG. 1;

FIG. 3 is a rear view in elevation of the coin-operated locker shown in FIGS. 1 and 2;

FIG. 4 is a view in elevation of the end opposite that shown in FIG. 1, and

FIG. 5 is a bottom plan view.

I claim:

The ornamental design for a coin-operated locker, as shown and described.
